STANLEY KONAT, OF DETROIT, MICHIGAN

COMBINATION LOCK

Application filed July 8, 1929. Serial No. 376,553.

This invention relates to locks, and particularly to combination locks.

An object of the invention is to adapt the bolt of a door lock to be freely actuated from the inside of a door, while preventing retraction of said bolt from the outside, except through manipulation of combination lock tumblers.

Another object is to effect the actual retraction of a lock bolt by manipulating a set of tumblers, rather than merely releasing said bolt by said tumblers for the purpose of subsequent manually effected retraction.

A further object is to provide for the normal projection of a lock bolt by a suitable spring, and to adapt said bolt to be automatically retracted responsive to manipulation of a set of tumblers, according to a predetermined combination.

Still another object is to provide a novel means for placing frictional restraint upon the disk tumblers of a combination lock, whereby each will retain its set position regardless of a subsequent actuation of the remaining tumblers.

A still further object is to form the parts of a combination lock of sheet metal stampings, such as may be inexpensively produced in quantity lots and are suited for compact assembly in a casing.

These and various other objects the invention attains by the construction hereinafter described and illustrated in the accompanying drawings, wherein:

Fig. 1 is an exterior view of that portion of a door to which the lock is applied.

Fig. 2 is a side view of the lock with its cover plate removed.

Fig. 3 is a view in side elevation of the tumbler mechanism of the lock, the casing cover, the bolt and guide plate for the bolt being removed.

Fig. 4 is a cross sectional view of the lock taken on the line 4—4 of Fig. 1.

Fig. 4a is a sectional view taken on line 4a—4a of Fig. 4.

Fig. 5 is a vertical sectional view of the same taken on the line 5—5 of Fig. 1.

Fig. 6 is a side view of the bolt and a spring

abutment member having a unitary connection with said bolt.

Fig. 7 is a section taken upon the line 7—7 of Fig. 6.

Fig. 8 is a side view of the several tumblers of the lock arranged in the order of their assembly and in unlocking position.

Fig. 9 is a side view of the tumbler which is initially set in an unlocking operation.

Fig. 10 is a side view of the tumbler which is next set.

Fig. 11 is a side view of the last slotted tumbler to be set.

Fig. 12 is a side view of the cam shaped tumbler which actuates all the others.

In these views, the reference character 1 designates a lock casing attached to the rear of a face plate 2 and mortised into a door 2a, as is common practice. One of the side walls 3 of said casing forms a cover plate removable for access to the lock mechanism and is normally attached to the casing by screws 4 or the like. A partition 5 parallel to the face plate is rigidly extended within said casing from top to bottom thereof. Slidable in said casing is a bolt comprising a rectangular sheet metal plate 6 formed with a large rectangular opening 7 and having a forwardly projecting shank 8 terminally carrying a relatively thick bolt head 9 beveled and fitted in an opening of the face plate, as is customary. Said bolt lies closely adjacent to the cover plate 3, and its portion 6 engages a sheet metal guide plate 10 removably seated in the casing, and having its top and bottom portions thickened to form guides for the bolt. (See Fig. 5.)

The bolt head 9 has a reduced rearward extension 13 about which is coiled a spring 14, normally opposing retraction of the bolt. Said extension has a longitudinal slot 15 through which passes a pin 16 establishing a lost motion connection between the bolt and a movable abutment for said spring. Said abutment is formed by a strip of metal, the mid portion 17 of which is U-shaped to slidably engage the extension 13. Said strip is upwardly and downwardly offset from the part 17 to seat the spring 14, and is extended forwardly above and below the spring as in-

dicated at 18, its terminal portions 19 being bent upwardly and downwardly to normally bear upon the face plate. The partition 17 of said abutment member is slidable. The latter is rearwardly urged by a pair of coiled springs 21 extending from its end portions 19 to the partition 5.

Rearward travel of said abutment member is normally resisted by a suitable number of coaxial tumbler disks, four being used in the 10 illustrated construction and designated respectively 22, 23, 24 and 25. The disk 22 is rigidly carried by a bushing 26 journaled in the fixed side wall of the casing, and on which the tumblers 23, 24 and 25 are freely rotatable. Said bushing is keyed, as indicated at 27, to a control stem 28 rotatively carried by the casing projecting at each side thereof. The disk 22 rigidly carries a pin 29 which 20 projects into arcuate slots 30 formed in the disks 23, 24 and 25, and differing in circumferential extent. (See Fig. 8.) The tumblers 23, 24 and 25 are furthermore each formed with a radial slot 31 registerable with 25 each other and with the abutment part 17, in certain positions of said tumblers to permit retraction of the abutment by the springs 21. The disk 22 has its periphery corresponding to that of the other tumblers through approximately 30 a semi-circle, and the balance of said periphery is of a reentrant cam form, as indicated at 32. Thus when the mid portion of the cam edge 32 is registered with the slots 31 and also with the rear portion 17 of said 35 abutment member, the latter is free for retraction by the springs 21. Also, the cam edge 32 adapts the disk 22 to project the abutment member 17 from a retracted position to that shown in Fig. 2.

The outer end of the stem 28 rigidly carries a handle 33, and adjacent thereto there is rigidly mounted upon said stem (as by means of the key 27) a dial plate 34 marginally graduated and numbered in accordance with common practice, as indicated at 35. Said plate may be adjusted by rotation of the handle 33 with reference to any suitable fixed index mark 36.

Upon the stem 28 within the opening 7 of the bolt, is loosely mounted a collar 37 which rigidly carries an approximately triangular cam 38 for retracting the bolt. Said collar is diametrically slotted as indicated at 39 for engagement by tongues 40 formed on one end of a sleeve 41, loosely engaging the stem 28 and journaled in the cover plate 3. Said sleeve projects at the inside of the door substantially coextensively with the stem 28 and rigidly carries a handle 42. Any suitable provision is made for holding said sleeve and handle in the described position. Thus a pin 43 which mounts the handle upon said sleeve may extend sufficiently into the latter to engage in an annular groove 44 formed in the end portion of the stem. Thus the

handle and sleeve are held in place on the stem while free to turn thereon.

When the tumblers 22, 23, 24 and 25 are being manipulated, it is necessary to prevent their frictional contact one with another in order that each tumbler, when properly set, may remain undisturbed by setting of the remaining tumblers. For this purpose, the invention provides elements spacing the tumblers from each other, and yieldably bearing peripherally on the tumblers. Thus the tumblers 23 and 25 are each engaged by a pair of elements 45 pivoted upon pins 46 rigidly secured to the fixed side wall of the casing above and below the tumblers. Said elements extend rearwardly from said pivot pins, and the rear ends of each pair of said elements are so connected through a tension spring 47 as to subject the disks 23 and 25 to a slight radial pressure. Furthermore, each element 45 carries a pair of spacer plates 48 marginally embracing the corresponding tumbler 23 or 25 and holding the tumblers 23, 24 and 25 out of contact. One of the elements 45 furthermore preferably carries a spring arm 49 secured at one end upon said element and bearing at its other end peripherally on the tumbler 24.

If the tumbler disks are not accurately of the same diameter, the abutment member 17, 18, 19 may undergo a very slight rearward actuation as each tumbler slot 31 is registered with the rear end of said member, and the resulting click might possibly indicate the proper setting of the tumblers to one unfamiliar with the combination. It is preferred therefore to mislead any person attempting an unauthorized manipulation of the lock by producing slight clicks at points in the rotation of the tumblers other than their unlocking points. Thus, the pressure-exerting edges of the elements 45 are made slightly V-shaped at their bearing points so that the latter may advance slightly into the slots 31 when registered therewith, producing slight clicks that will have the desired effect.

In the use of the described lock, when the inside handle 42 is turned, the sleeve 41 turns therewith and through its tongue and slot connection to the collar 37, rocks the cam 38. The upper or lower ends of the latter, (according to the direction of turning of the handle), thus exert pressure on the rear edge of the opening 7 to retract the bolt. During such operation, the abutment member 17, 18, 19 maintains its normal position, since its rear end engages the edges of the tumbler disks. The spring 14 will be compressed by such retraction, and on release of the inside handle again projects the bolt.

To open the door from the outside, the dial plate 34 is manipulated by the handle 33 to successively register certain of its marginal markings with the index mark 36. The in-

initial turning of the dial acts through the pin 29 on the tumbler 25 (which has the longest arcuate slot) to bring the radial slot thereof into registration with the rear end 17 of the abutment member. Rotation of the dial then being reversed, said pin actuates the tumbler 24 to register its radial slot with that of the dial 25. A further reversal of the dial plate similarly brings the radial slot of the tumbler 23 into proper position, and a final reversal of said plate registers the reentrant cam edge of the tumbler 22 with the members 17, 18, 19, allowing the springs 21 to retract said member. The latter acts through the pin 16 upon the bolt to also retract the latter, without increased stress upon the spring 14. Thus, it is seen that the retraction of the bolt responsive to manipulation of the tumblers is entirely automatic and involve no other operation than that of turning the handle and dial to the proper successive positions.

Almost all of the described parts may be cheaply stamped from sheet metal, and because of the slight thickness of this material, said parts may be very compactly assembled in a casing.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

35 What I claim is:

1. A lock comprising a casing, a bolt slideable in said casing, a spring normally projecting the bolt, a retractible abutment for said spring, means establishing a lost motion connection between said bolt and abutment whereby the bolt may be projected by said spring in the normal position of the abutment, and a retraction of the abutment is adapted to retract the bolt, means yieldably urging said abutment rearwardly, a plurality of coaxial tumblers normally resisting rearward actuation of said abutment and co-acting in certain set positions to permit such actuation, means operable from one side of the casing for setting said tumblers and means operable from the other side of the casing for freely retracting the bolt relative to said abutment.

55 2. A lock comprising a casing, a bolt slideable in said casing, and having a longitudinally slotted portion, a spring embracing said portion, projecting the bolt, an abutment for the rear end of said spring, a pin carried by said abutment extending through said slot, means urging said abutment rearwardly, a plurality of coaxial tumblers normally resisting rearward actuation of said abutment and having set positions permitting such actuation, means actuatable from one side of the casing for setting said tumblers,

and means actuatable from the other side of the casing for freely retracting said bolt relative to said abutment.

3. A lock comprising a casing, a bolt slideable in said casing, a spring normally projecting the bolt, an abutment for said spring rearwardly movable to render said spring ineffective, means establishing a lost motion connection between said bolt and abutment, means yieldably urging said abutment rearwardly, a plurality of tumblers mounted rearwardly of said abutment and normally resisting its rearward travel, a stem rotative in said casing coaxially mounting said tumblers, means carried by said stem for setting said tumblers to permit retraction of said abutment, a member carried by said stem at one side of the casing for rotating the stem to set said tumblers, means rotative upon said stem for retracting the bolt independently of said abutment, and an actuating member for said means at the other side of said casing.

4. A lock comprising a plurality of coaxial disk tumblers and an element pivoted adjacent to said tumblers and peripherally bearing upon one thereof and having portions spacing said tumblers from the adjoining tumblers, and means yieldably maintaining pressure of said element upon the tumbler engaged thereby.

5. A lock comprising a casing, a bolt slideable in said casing and provided with a head at its forward end, a coiled spring located rearwardly of said head and forwardly acting on said head, an abutment engaging the rear end of said spring comprising portions forwardly projecting at opposite sides of said spring, and comprising outward extensions from the forward ends of said portions, a pair of springs engaged with said extensions and urging the abutment rearwardly, a plurality of coaxial tumblers located rearwardly of said abutment and each peripherally formed with a notch, said notches being registerable through rotation of said tumblers with said abutment to permit its retraction, means establishing a lost motion connection between said bolt and abutment permitting retracting of the bolt independently of the abutment, and adapting the abutment to retract the bolt, and means for retracting the bolt independently of said abutment.

In testimony whereof I sign this specification.

STANLEY KONAT.
